UNITED STATES PATENT OFFICE.

FRANCIS ROBERT BOETTNER, OF CHICAGO, ILLINOIS.

IMPROVED APPARATUS FOR WORKING SHIPS' PUMPS.

Specification forming part of Letters Patent No. 38,460, dated May 12, 1863.

To all whom it may concern:

Be it known that I, FRANCIS R. BOETTNER, of Chicago, in the county of Cook and State of Illinois, have invented a new and useful Improvement in the Application of Pumps to Ships and other Vessels; and I do hereby declare that the following is a full, clear, and exact description of the same, reference being had to the accompanying drawings, forming a part of this specification, in which—

Figure 1 is a transverse vertical section of a portion of a vessel, illustrating the application of my invention. Figs. 2 and 3 are vertical sections, at right angles to each other, of the valve-box and valve and pipe-connections, which constitute one of the most essential features of my invention.

Similar letters of reference indicate corresponding parts in the several figures.

The principal object of my invention is to provide for the pumping of the bilge-water from all parts of a vessel, whether on an even keel or careening over to one side or the other; and to this end my invention consists, first, in leading pipes in various parts of a vessel to one common air-tight chamber, with which the pump or pumps are connected, thereby enabling the water to be drawn directly from all parts of the vessel by one pump or set of pumps; secondly, in the employment within such a chamber of a valve or valves so applied under the control of a hanging weight as to cut off from communication with the said chamber such of the pipes leading from different parts of the vessel as may have their mouths left uncovered with water by the change of position of the vessel, and to open to communication with the said chamber such of the said pipes as may have their mouths covered with water, thereby insuring the pump or pumps drawing water while any remains in the vessel, and preventing them from drawing air while any water remains.

To enable others skilled in the art to make and use my invention, I will proceed to describe it with reference to the drawings.

A represents a portion of the hull of a vessel; B, a portion of the deck. C is the air-tight chamber, with which the pipes E F F', for collecting the bilge-water, are connected. This chamber is represented as supported upon the deck of the vessel by means of three

short pipes, e f f', which are connected with a suitable base, D, which is bolted to the deck B. The pipes E F F' are connected in a suitable manner with the pipes e f f'. The pipe E is intended to run down alongside of the keelson, and the pipes F F' into the bilge of the vessel on opposite sides. The pump or pumps are to be placed on the top of the chamber C, or arranged in any other convenient manner relatively thereto, for the connection of the suction-pipes G with the said chamber.

The chamber C may be of various forms, and the valve H, which is employed to open and close the communications between the pipes e f f' and the said chamber, of various kinds. The said chamber is represented of the form of a horizontal cylinder, the axis of which is arranged lengthwise of the vessel, and the valve H of the form of an arc fitted to a seat, which is formed for its reception by boring the said cylinder, the said valve being attached by an arm, J, to a shaft, I, which is concentric with the said cylinder, and which works in suitable bearings in the heads thereof, one end of the said shaft passing through a stuffing-box in its respective head for the attachment to it outside of the cylinder of the pendulous weight K, which keeps the valve always at the bottom of the cylinder and below the shaft, whatever the position of the vessel. The pipes e f f' terminate in ports in the valve-seat, the port of e being at the bottom of the cylinder, and the ports of f and f' being at equal distances from and on opposite sides of e, as shown in Fig. 2, and there is a corresponding port, g, in the valve itself, which is always kept by the weight K directly below the shaft. When the vessel is on an even keel, the port g is directly over the central port, and the central pipes, e E, only are open, the side pipes, f F and f' F', being closed by the valve; but when the vessel careens over to one side or the other a certain distance, the port of the pipes f F or f' F', according to the direction in which the careening takes place, is brought under the port g, the central port being either wholly or partly closed, and the uppermost port in the seat, the mouth of whose pipe F' or F is uncovered by the bilge-water, remaining closed.

In order to keep the valve in contact with its seat, notwithstanding any wear that may occur,

the valve is fitted to the arm J in such manner that a spring, L, coiled upon the said arm, may press it gently against the seat. What I claim as my invention, and desire to secure by Letters Patent, is—

1. Leading pipes from different parts of a ship or other vessel to one common chamber, C, with which the pump or pumps or suction-pipe of the pump or pumps is connected, substantially as and for the purpose herein specified.
2. The employment, within such chamber C, of a valve or valves so applied in relation to suitably-arranged ports, in connection with the

pipes leading from different parts of the vessel, and so controlled by an oscillatory movable weight, as to open communication between such chamber and the pipe or pipes whose mouths are covered with the bilge-water, and to close communication between such chamber and the pipe or pipes which, owing to the position of the vessel, have their mouths uncovered by the said water, substantially as herein specified.

FRANCIS ROBERT BOETTNER.
